UNITED STATES PATENT OFFICE.

EMIL H. LARKINS, OF CLEVELAND, OHIO.

KEY FASTENER.

Application filed March 2, 1922. Serial No. 540,439.

To all whom it may concern:

Be it known that I, EMIL H. LARKINS, a citizen of the United States, residing at Cleveland, in the county of Cuyahoga and 5 State of Ohio, have invented a new and useful Key Fastener, of which the following is a specification.

This invention relates to improvements in key-fasteners, and pertains more especially 10 to a key-fastener adapted to attach the bow or handle of a key, which projects at one side of a door from within the key-hole in the door, to the shank of the door-knob at said side of the door.

15 One object of this invention is to have my improved key-fastener not only comprising an upwardly bowed resilient member which is adapted to embrace the upper portion of and seat on said shank and terminates at one 20 end in a downwardly extending arm which has its lower end portion bent as required to form a hook arranged to extend under and thence upwardly through the bow or handle of the key, but to provide the key-fastener, 25 with a handle-forming member which has one end portion thereof arranged adjacent and extending outwardly from said end of the shank-embraceable member of the key- 30 fastener and comprises an upwardly bowed portion which extends from said end portion to and over the opposite end and circumferentially of and is spaced from said shank-embraceable member and terminates in the last-mentioned end of said shank- 35 embraceable member.

Another object is to facilitate the manufacture of my improved key-fastener, and to render the key-fastener readily applicable to and removable from the shank of the 40 door-knob.

Another object is to render my improved key-fastener reliable in its operation and attractive in appearance.

With these objects in view, and to attain 45 any other object hereinafter appearing, this invention consists in certain peculiarities in the contour and relative arrangement of the different portions of the key-fastener hereinafter described in this specification, pointed out in the claims, and illustrated in the accompanying drawings.

In said drawings, Figure 1 is an elevation showing an edge of the lock-containing portion of a door and shows the key in the position it occupies upon actuating the lock-

bolt into its operative position and illustrates the application of my improved key-fastener to the bow or handle of said key and to the shank of the adjacent door-knob. Fig. 2 is a vertical section taken along the 60 line 2-2 in Fig. 1.

Referring to said drawings, 5 indicates a door containing a lock 6, and 7 and 8 indicate the latch and lock-bolt respectively of said lock. The bolt 8 is shown in its locking or operative position, and 9 indicates the key-hole in the door. A key 12 projects at one side of the door from within said key-hole and is shown in the position it occupies upon the actuation of the bolt 8 into 70 its operative position, and my improved key-fastener is shown attaching the bow or handle 13 of said key to the shank 16 of the door-knob 15 at said side of the door and consists of a suitably bent single piece of 75 wire having suitable length and stiffness and comprises an upwardly bowed resilient member 17 formed by the central portion of said piece of wire and adapted to closely embrace the upper portion of and shown 80 mounted or seated on the shank 16 which is mounted on the knob-spindle 18 in the usual manner.

One end portion 19 of said piece of wire is arranged below the shank-embraceable central portion 17 of said piece of wire and bent as required to form a hook 20 shown extending under and thence upwardly through the bow or handle 13 of the key to be fastened when said key is in the position shown 90 upon the actuation of the bolt 8 into its operative position.

The other or upper end portion of said piece of wire is arranged in the main above the shank-embraceable portion 17 and preferably not only bent to have its outer end 95 disposed substantially in contact with the outer circumferential surface of said shank-embraceable portion but bent to form a handle arranged largely above and extending circumferentially of said shank-embraceable portion. Preferably said last-mentioned end portion of said piece of wire is bent to form a handle comprising an upwardly bowed member 23 which is spaced in 100 the main upwardly from and extends circumferentially of the shank-embraceable portion 17.

To remove the key-fastener from the shank 16 of the door-knob the handle-form-

ing member of the key-fastener is taken hold of and actuated as required to unseat the shank-embraceable member 17, against the action of its resilience, from said shank, and 5 obviously the key-fastener, upon removing it from said shank, is free to be lowered to remove the hook 20 from the bow or handle 13 of the key.

What I claim is—

- 10 1. A key-fastener consisting of a single piece of wire which has a bowed and resili-ent central portion arranged to embrace the upper portion of and seat on the shank of a door-knob and has one end portion there-15 of arranged below said shank-embrace-able portion and bent to form a hook ar-ranged to extend under and thence upwardly through the bow or handle of a key to be fastened, said piece of wire having its up-20 per or opposite end portion bent to form a handle arranged largely above and extend-

ing in the main circumferentially of the aforesaid shank-embraceable portion.

2. A key-fastener consisting of a single piece of wire which has a bowed and resili-ent intermediate portion arranged to em-brace the upper portion of and seat on the shank of a door-knob and has one end portion thereof arranged below said shank-embraceable portion and bent to form a hook ar-ranged to extend under and thence upwardly through the bow or handle of a key to be fastened, said piece of wire having its upper or opposite end portion bent to form a handle comprising an upwardly bowed portion extending circumferentially of and spaced from the afore-said shank-embraceable portion.

In testimony whereof, I sign the foregoing specification, this 28th day of February, 1922.

EMIL H. LARKINS.
